UNITED STATES PATENT OFFICE.

WILLIAM SPARKS, OF JACKSON, MICHIGAN, ASSIGNOR TO THE SPARKS-WITHING-
TON COMPANY, OF CLEVELAND, OHIO, A CORPORATION OF OHIO.

RADIATOR.

1,397,116.

Specification of Letters Patent. Patented Nov. 15, 1921.

Application filed August 4, 1917. Serial No. 184,442.

To all whom it may concern:

Be it known that I, WILLIAM SPARKS, a citizen of the United States of America, and resident of Jackson, in the county of Jackson, in the State of Michigan, have invented new and useful Improvements in Radiators, of which the following, taken in connection with the accompanying drawings, is a full, clear, and exact description.

- 10 This invention relates to certain improvements in radiators for liquid-cooled internal combustion engines commonly employed as the motive power for automobiles, aeroplanes and analogous vehicles, in which 15 the radiator is exposed to more or less liability to injury, as for example in war machines where the radiators are liable to be punctured by bullets, fragments of shrapnel and other external objects which, under the 20 present construction, would render the entire radiator useless.

The primary object of my present invention is to divide radiators of this type into a series of separate or independent circulatory units or sections, each having a separate valved inlet and valved exit so that in case any one or more of said sections or units may become impaired, it may be readily cut out of the circulatory system as 30 a whole without affecting the free circulation of the cooling agent through the remaining sections, thereby permitting the continued operation of the engine without material delay and still maintaining a sufficient circulation of the cooling agent to prevent overheating of the engine.

Another object is to provide simple means for assembling and retaining the entire series of radiator units or sections in fixed 40 relation, and at the same time to allow free expansion or contraction of either unit without overstraining or loosening the connections between them.

Other objects and uses relating to specific 45 parts of the circulatory system will be brought out in the following description.

In the drawings—

Figure 1 is a perspective view of a radiator embodying the features of my invention.

50 Fig. 2 is an enlarged vertical sectional view, partly broken away, on line 2—2, Fig. 1.

Fig. 3 is a horizontal sectional view taken in the plane of line 3—3, Fig. 2.

55 As illustrated, this radiator comprises a

series of similar interchangeable cellular units or sections —1— of hollow, vertically-elongated formation and arranged side by side in an upright position so as to lie in substantially the same vertical plane in close 60 juxtaposition, the entire series being bound together or embraced by a metal band —2— extending across the bottom and top of the entire series and along the outer upright faces of the end sections and provided with 65 lower and upper inturned flanges —3— lying against the front faces of the adjacent portions of the sections to additionally support the same.

Each radiator section or unit is rigidly 70 secured to the external frame or band —1— by a separate set of clamping screws —4— which are passed through apertures in the lower and upper sides of said frame and engaged in threaded sockets —5— in the 75 adjacent portions of the radiator section, as shown more clearly in Fig. 2, each section being also provided with an inlet —6— and an exit —7— located, respectively, in the upper and lower portions of the rear side 80 of the radiator, the inlets being arranged near the top and the exits near the bottom.

The inlets of the several sections are connected by branch pipes —8— to a distributing pipe or header —9— which is connected 85 to the engine, not shown, by the usual up-flow pipe, as —10—, the header being also provided with a separate inlet —11— into which the cooling agent may be admitted in filling the circulatory system, said inlet 90 —11— being normally closed by a screw cap —12—.

The exits —7— of the several units are connected by branch pipes —13— to a separate distributing pipe or header —14— 95 similar to the header —9—, said header being connected by a return flow pipe —15— to the engine, not shown.

Each of the branch inlet and exit pipes —8— and —13— is provided with a separate 100 valve —16— for controlling the flow of the cooling agent to and from the corresponding radiator unit or section, thus permitting any one of the sections which may become impaired to be cut out from the rest of the 105 circulatory system and permitting the free flow of the cooling agent through the remaining sections.

It is also evident that in case any one of the radiator sections becomes impaired, 110

it may be readily disconnected and removed and replaced by a new one without material loss of time or displacing any of the other units.

5 I claim—

A radiator comprising a plurality of separate radiator units arranged side by side and each unit comprising an upper water chamber and a lower water chamber connected by a water tube, one of said water chambers provided with an inlet for the fluid and the other of said water chambers provided with an outlet for fluid, a source of fluid connected to the inlet of each of said

units and valves for disconnecting any one 15 of said units from said source of fluid, a discharge for fluid connected to the outlet from each of said units, valves for disconnecting any one of said units from the said discharge for fluid, a band extending around 20 the assembled radiator units, and means for securing each unit to the band.

In witness whereof I have hereunto set my hand this 26th day of July, 1917.

WILLIAM SPARKS.

Witnesses:

LILLIAN WUNDERLICH,
P. H. WITTINGTON.
